(57) **CLAIM**

The ornamental design for an actuator for a fluid dispenser, as shown and described.

DESCRIPTION

FIG. 1 is a perspective view of an actuator for a fluid dispenser according to the invention;

FIG. 2 is a front view thereof;

FIG. 3 is a top view thereof;

FIG. 4 is a bottom view thereof;

FIG. 5 is a left-side view thereof; and,

FIG. 6 is a right-side view thereof.
